(57) **CLAIM**

The ornamental design for a LED panel light set, as shown and described.

DESCRIPTION

FIG. 1 is a front view that shows three components of a LED panel light set;

FIG. 2 is a front elevational view of a first component of the LED panel light set; the second and the third components are omitted for clearer illustration;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof;

FIG. 9 is a front elevational view of a second component of the LED panel light set; the first and the third components are omitted for clearer illustration;

FIG. 10 is a rear elevational view thereof;

FIG. 11 is a left side view thereof;

FIG. 12 is a right side view thereof;

FIG. 13 is a top plan view thereof;

FIG. 14 is a bottom plan view thereof;

FIG. 15 is a perspective view thereof;

FIG. 16 is a front elevational view of a third component of the LED panel light set; the first and the second components are omitted for clearer illustration;

FIG. 17 is a rear elevational view thereof;

FIG. 18 is a left side view thereof;

FIG. 19 is a right side view thereof;

FIG. 20 is a top plan view thereof;

FIG. 21 is a bottom plan view thereof;

FIG. 22 is a perspective view thereof;

FIG. 23 is a front elevational view of the LED panel light set in a first state of use which is a combination of the first and the second components;

FIG. 24 is a rear elevational view thereof;

FIG. 25 is a left side view thereof;

FIG. 26 is a right side view thereof;

FIG. 27 is a top plan view thereof;

FIG. 28 is a bottom plan view thereof;

FIG. 29 is a front perspective view thereof;

FIG. 30 is a rear perspective view thereof;

FIG. 31 is a front elevational view of the LED panel light set in an alternative state of use which is a combination of the first and the third components;

FIG. 32 is a rear elevational view thereof;

FIG. 33 is a left side view thereof;

FIG. 34 is a right side view thereof;

FIG. 35 is a top plan view thereof;

FIG. 36 is a bottom plan view thereof;

FIG. 37 is a front perspective view thereof; and,

FIG. 38 is a rear perspective view thereof.
